CALCULATING MACHINE

Robert L. Muller, Detroit, Mich., assignor to
 Burroughs Adding Machine Company, Detroit,
 Mich., a corporation of Michigan

Application December 1, 1937, Serial No. 177,435

3 Claims. (Cl. 235—60)

This invention relates to calculating machines and more particularly to a bookkeeping type of calculating machine for printing and making the necessary bookkeeping calculations and entries for the different columns of a bookkeeping form.

One type of work for which these machines are used is that of posting customers' accounts in banks. This work is so voluminous in the large banks that a continual demand arises for greater speed and more automatic operation. Posting of the account of a customer may involve the posting of one or several checks only; or the posting of a deposit only; or the posting of one or more checks and a deposit. After each type of posting a new balance must be obtained. These variations in posting require that the machine be appropriately conditioned for addition, for subtraction, and for total taking, and the various items must be printed in the proper columns. But, no matter what the character of the account to be posted, as little time as possible must be used in the manipulation of the machine and in its automatic operation.

Another factor that enters is that the banks do not want any of their customers to overdraw their accounts. Accordingly, the bookkeeper must be notified immediately when an account is overdrawn and the necessity for this notification must not interfere with the rapid and automatic operation of the machine. Furthermore, it should take place before the bookkeeping operations have gone very far because the banks do not ordinarily carry overdrawn accounts. Instead, they do not accept the check that overdraws the account. The present invention has been devised to solve this problem.

The general object of the invention is to provide an improved automatic calculating machine.

A more particular object is to provide a machine in which totals are taken automatically and one in which, when the total is negative, automatic operation of the machine will be stopped before the total is taken, thereby notifying the operator that a negative total exists before a new balance is taken.

Another object is to provide an improved calculating machine in which, when the operator manipulates the motor bar to initiate a machine cycle for the posting of a check, he may do so in such a way as to either cause the paper carriage, after said check has been subtracted, to move to the "deposit" column where the machine will be automatically pre-conditioned for total taking and a total then taken automatically in

the "balance" or total column, or he can manipulate the bar in a manner to cause the carriage to move to the "deposit" column where it as well as the automatic operation of the machine will stop to permit the entry of a deposit.

Other and further objects and their resultant advantages will be apparent from the following description given in connection with the drawings in which:

10 Figure 1 is a right side elevation of a machine embodying this invention, the machine elements being in normal position;

Fig. 2 is a partial right side elevation illustrating the motor controls and associated mechanisms with the auxiliary motor bar latched down and with the machine parts at the end of a forward machine stroke;

Fig. 3 is a fragmentary detail in side elevation of the auxiliary motor bar and associated parts illustrating the auxiliary motor bar held down in fully depressed position;

Fig. 4 is a fragmentary left side elevation or detail of the total key and portions of the negative total lock controls;

Fig. 5 is a fragmentary enlarged detail in side elevation of the automatic total-taking means illustrating the latter in tripped position, but prior to machine operation;

Fig. 6 is a diagrammatic illustration of four 30 different types of transactions a machine embodying the principles of this invention is capable of performing.

Fig. 7 is a left side elevation showing the subtract controlling mechanism of the machine to which the invention is applied.

Fig. 8 is a detail side elevation of one of the interlocks on the machine.

The illustrated embodiment of this invention for accomplishing the heretofore mentioned desired results is shown as applied to a Burroughs high keyboard machine of the type illustrated in many known patents, as, for example, the Fasinski Patents No. 1,778,506 and No. 1,911,768, for which reason the general construction of the machine will be described only very briefly, reference being had to the foregoing and other issued patents for further details of construction. It will be obvious to those skilled in the art that the invention may be applied to other types of calculating machines.

General Construction

The machine, which is illustrated generally in Fig. 1, is of a type which, after it is properly conditioned, is given a cycle of operation during

which its various functions are performed. It may be cycled manually by means of a hand crank but most of the present day machines are provided with a power operated driving means that is actuated by an electric motor 23 (Fig. 1). This motor drives the machine through a normally disengaged clutch in the housing 24, which clutch is connected through the necessary shafts, cranks and levers to the main drive shaft that, in turn, is suitably connected to other parts of the machine to operate them. The motor and clutch are normally controlled by the motor bar M which, when depressed, starts the motor and engages the clutch to cause said motor to give the machine a single cycle of operation. During the first half cycle, or "forward stroke," of the machine the motor positively drives said machine and tensions the springs 23a. During the second half cycle, the motor drive simply moves so as not to interfere with the machine operation, the actual power being furnished by the springs 23a for said second half cycle or return stroke. The motor and its controls are described in detail in Vincent Patent No. 866,750, where, however, the motor is shown as a continuously running motor. The motor employed on the present day machine is a normally inactive motor whose circuit is closed by depression of said motor bar as disclosed in Bindschedler Patents Nos. 1,658,036 and 1,773-164. Repeat machine cycles may be obtained by mechanism such as disclosed in Muller 1,397,774.

An amount indexing means is provided for enabling items or amounts to be indexed in the machine. This indexing means comprises a plurality of depressible amount keys 1, of which, in a bank machine, there are usually seventeen rows of nine keys each. When one of these keys is depressed, it rocks a bell crank 2 (Fig. 5) to set an index stop in the form of a wire 3 which arrests the corresponding actuator 4 in a position corresponding to the digital value of the key depressed. The actuator is carried on the forward end of a pivoted lever 6, the rear end of which is shown in Fig. 1. Said rear end carries a plurality of type 8. At the beginning of a machine cycle, the actuators are normally released and they descend to differential positions. This also differentially positions the type and, near the end of the first half of the machine cycle, said type are normally struck by the hammers 9 of a printing mechanism that causes printing to occur upon record material held about the platen 10.

The machine has a main add-subtract registering mechanism, sometimes called a "crossfooter," which comprises a set of add pinions 11 meshing with a set of subtract pinions 12. Said registering mechanism is of the "tumbling" type; that is, it may be tumbled or rocked from an "add position" in which the add pinions are in active position for connection with the actuators to a "subtract position" where the subtract pinions are in active position, and vice versa. Said registering mechanism is normally in "add" position, but an add-subtract control means may be conditioned either manually or automatically as described in Pasinski No. 1,778,506 so that said registering mechanism will assume a subtract position. Said mechanism is best illustrated in Fig. 7. It includes a subtract lever 14 which is used when the machine is to be conditioned for subtraction manually. For automatic control, the carriage has a cam roll 14a which, when the carriage reaches a predetermined position, rocks

5 a cam lever 14b that is connected through link 14c to the subtract lever 14. When the subtract lever is moved forward either manually or automatically, it raises a link 14d that lifts the rear end of a pitman 14e. This places a shoulder 14f in the path of a stud 14g on a member 14k that is rocked during each machine cycle. Said stud 14g engages the shoulder 14f during the first half 10 of the machine cycle and pulls a pivoted lever 14m clockwise which tumbles the "crossfooter" from add to subtract position. The machine is normally conditioned for addition owing to the fact that a spring 14r pulls rearward on a lever 14s connected by a stud and slot connection 14t to the link 14c that is connected to the subtract lever 14. After said subtract lever is moved to subtract position it is locked in such position during the machine cycle but, at the end of said cycle, it is released, whereupon the spring 14r pulls said lever to add position with the result 15 that, during the first part of the next cycle, the crossfooter will be tumbled to add position unless the operator or the carriage again indexes said control means for subtraction.

25 A tens-transfer mechanism is associated with said registering mechanism, said tens-transfer mechanism being of a type employing an extra step of movement of the actuators and being capable of effecting both "carries" and "borrows," as described in Rinsche No. 1,172,484. It is operated by tens-transfer projections 16 and 17 (Fig. 1) on the add and subtract pinions.

30 A plurality of multiple registers 15 are provided as described in Pasinski No. 1,911,768, which registers may be selected automatically under the control of the paper carriage as described in said patent.

35 Printing is controlled so that it may occur in different columns on record material supported on the machine. For this purpose a columnar-printing control means is provided which is in the form of a traveling paper carriage 20, together with means for moving and controlling the movement of said carriage. The carriage is urged across the machine to the left, viewing the machine from the front, by a spring drum 21 (Fig. 7) and this movement, called movement in tabulating direction, is controlled by a tabulating mechanism, portions of which are shown in Fig. 1, and which is described in Rinsche No. 1,516,685. Said mechanism includes a "tab bar" 28 (Fig. 1) carrying a plurality of "tab stops" 26 which engage an abutment 26b. Normally, near the end of each machine cycle, the "tab bar" 28 is rocked clockwise (Fig. 1) which disengages the tab stop and the abutment. The carriage immediately starts to move, but the tab bar is released almost immediately after being rocked and it returns to normal so that the next tab stop hits the abutment and arrests the carriage. Thus, 40 normally, the carriage moves from one columnar position to another near the end of each machine cycle. The carriage is returned across the machine by a power operated carriage return mechanism, of which a part is shown at 27 in Fig. 1 and which is described in detail in Rinsche No. 1,580,534.

45 The record material is held on the paper carriage by being held about the platen 10. The paper carriage is of the front-feed type such as described in British Patent No. 382,623 of 1930. In this type of carriage, a record sheet is maintained about the platen for a long series of entries, but the individual customers' ledger cards 50 are inserted and removed from time to time. To

facilitate such insertion and removal, a front-feed means is provided which is automatically controlled and power operated so that it will move from closed to open throat position and vice versa without any attention on the part of the operator. Portions of the front-feed mechanism are shown at 28 and 28^a in Fig. 1.

Both positive and true negative totals may be taken directly from the main registering mechanism or "crossfooter," and, for this purpose, the machine is provided with a total-taking control means usually governed by the total key T. When a positive total is taken, the registering mechanism must be in add position so that the total may be taken from the add pinions. When the total is negative, the registering mechanism must be in subtract position for taking the total in order that said total may be taken directly from the subtract pinions. A suitable "fugitive 1" mechanism is provided for insuring that the totals will be numerically correct, said mechanism being of the type illustrated in Rinsche No 1,172,484.

Before describing the mechanism of the present invention, it will be helpful to first describe an example of the work that may be performed in order that the purpose of the various mechanisms may be more easily understood when they are later described.

Examples of work

In Fig. 6, there are illustrated four typical transactions that may arise in bank posting, these transactions being lettered A, B, C and D.

Transaction A involves the posting of two checks against a customer's account, leaving a positive balance. The transaction starts with the paper carriage in column 1 where the customer's old balance is entered. This is called the "pick-up" column. The operator indexes the customer's old balance of \$100.00 by depressing the proper amount keys, after which he depresses the regular motor bar M to cause the machine to be given a cycle of operation. During this cycle, the amount of the old balance, \$100.00, is entered positively in the "crossfooter" and, near the end of the cycle, the paper carriage tabulates to its column 2 position where a check is to be posted. Since the check must be subtracted, the machine must be in subtract condition and, in the present machine, the paper carriage automatically conditions the machine for subtraction. The check of \$50.00 is then indexed on the amount keys and the motor bar M is again depressed to cause a machine cycle during which the amount of the check, \$50.00, is subtracted from the "crossfooter." Near the end of the cycle, the carriage tabulates to column 3, where the machine is again conditioned for subtraction by the carriage, this being a second check column. The amount of the second check, \$25.00, is indexed on the amount keys. However, since no deposit is to be entered, there is no occasion for stopping the carriage in the "deposit" column. It can go directly to the "balance" column as far as the operator is concerned. At the end of the cycle in column 3, the machine will be in subtract condition. Since the next operation is the taking of a new balance, said machine should be in add condition because the balance is positive. In the present invention, the operator depresses the special motor bar M' and releases it immediately which causes the machine to be given a cycle in column 3 where the check of \$25.00 is subtracted from the crossfooter, after which the car-

riage moves to the "deposit" column where it cycles automatically to change said crossfooter from subtract to add position. Thereafter, the carriage tabulates to the "balance" column where a total is automatically taken and printed. After the taking of this total, the carriage is automatically returned across the machine by the carriage return mechanism so that it will be in position for a new transaction and, during this return, the front-feed throat is opened so that the operator may remove the customer's ledger sheet and insert another.

In a similar transaction involving the posting of only one check, the operator would depress the special motor bar M' in column 2, which would cause the carriage to move directly to the "deposit" column where the same automatic operation would take place as above described.

Transaction B involves the posting of one check and the entry of one deposit, leaving a positive balance in the customer's account. The old balance of \$100.00 is indexed as before, the regular motor bar M is depressed, the machine cycles to add the old balance of \$100.00 in the crossfooter, and the carriage moves to column 2 where the amount keys are depressed to enter the amount of the check, \$25.00. Since this transaction involves the entry of a deposit, the operator must have the carriage stop in the "deposit" column. Accordingly, with the present invention, he again depresses the special motor bar M', but he holds said bar depressed a short time, with the result that the paper carriage will move directly to the "deposit" column and stop. The cycling of the machine will be stopped also. The operator then indexes the amount of the deposit, \$50.00, on the amount keys and depresses the regular motor bar M. The machine is given a cycle of operation during which the crossfooter tumbles from subtract to add position and the deposit of \$50.00 is added in said crossfooter. Near the end of the machine cycle, the carriage tabulates to the "balance" column where an automatic total-taking cycle occurs to take the new total, after which the carriage is returned across the machine and the throat opened as above described.

Transaction C involves the posting of a check that overdraws the customer's account even though a deposit is also entered. The operations proceed as before, that is, the amount of the old balance, \$100.00, is indexed in the "pickup" column, and the regular motor bar is depressed, after which the carriage moves to the column 2 position. The check of \$200.00 is then indexed and, since a deposit is to be posted next, the operator depresses the special motor bar M' and holds it depressed a short time. The check of \$200.00 is subtracted from the crossfooter during the machine cycle, and the crossfooter goes negative. Near the end of the cycle, the carriage moves directly to the "deposit" column where it stops and no further cycling of the machine occurs. The operator then indexes the amount of the deposit, \$25.00, on the amount keys and depresses the regular motor bar M, which causes a machine cycle during which the crossfooter changes from subtract to add position and the deposit of \$25.00 is added in said "crossfooter." The carriage then moves to the "balance" column. Normally, as above described, when the carriage reaches the "balance" column, a total is automatically taken, but, in transaction C, the crossfooter contains a negative total and, with

the mechanism of the present invention, operation of the machine is stopped. The operator immediately knows that an overdraft has occurred. He may then stop the posting, strike out the entries and send the check for \$200.00 through "N. S. F." channels. If he desires to print the negative total, he may do so by moving the subtract lever to subtract position, and depressing the motor bar M to give the machine a spacing cycle to get the crossfooter to subtract position. He then depresses the total key and causes a total taking cycle which will cause the negative total to be printed, after which the carriage will return across the machine and the throat be opened as before.

Transaction D involves the posting of a check that overdraws the customer's account but no deposit is entered. The old balance of \$100.00 is indexed on the amount keys in the "pickup" column, and the main motor bar M depressed, whereupon the machine cycles to add the balance in the crossfooter and the carriage moves to column 2. The amount of the check, \$200.00, is indexed on the amount keys but, since the operator does not need to enter a deposit, he depresses the special motor bar M' and releases it immediately. This causes a machine cycle during which the \$200.00 is subtracted from the crossfooter which goes negative, after which the carriage moves directly to the "deposit" column where the machine is given a cycle automatically to change it to add condition, after which the carriage moves to the "balance" column, but, since the register contains a negative total, no automatic machine cycle occurs. The operator is again notified that an overdraft exists and he can obtain it, if he desires, as above explained.

The general structure of the machine and typical examples of work having been described, an explanation of the mechanism will now be given in more detail.

Control of carriage movement

The special motor bar M' controls the movement of the paper carriage from the column in which said bar is depressed to the "deposit" column in the following manner:

Depression of the special motor bar lowers its stem 29 (Figs. 2 and 3) which is slidably supported at its upper end by a stud and slot connection 30 and which is pivoted at its lower end to a crank arm 31. Pivoted at 34 on the stem 29 is a bell crank 33 which moves bodily downward with the stem as the same is lowered. The bell crank 33 is connected to the rear lever 36 of the main motor bar mechanism, said lever 36 being connected to another lever 37 and the two levers 36 and 37 being moved when the main motor bar M is depressed. A stud 32 carried on the stem 29 of the special motor bar M' and engaging the upper edge of the forward arm of the bell crank 33 prevents the bell crank from rocking clockwise about its pivot 34 as the special motor bar M' is depressed so that the downward movement of the bell crank 33 as the special motor bar M' is depressed causes the main motor bar M to be depressed at the same time. The bell crank 33 also serves as an interlock to prevent depression of the special motor bar M' while the main motor bar is in depressed position after being depressed alone. When the main motor bar is depressed alone, the bell crank 33 is rocked counterclockwise about its pivot 34 so that its lower arm moves over the upper surface of the square head of

stud 30. If, then, an attempt is made to depress the special motor bar M' before the main motor bar M returns to normal, the stem 29 cannot move downward because the end of the vertical arm of bell crank 33 is blocked by stud 30. The bell crank 33 acting in conjunction with the stud 30 serves to prevent immediate full restoration of the special motor bar M' if the operator withdraws manual pressure from said motor bar immediately after depressing it. When the special motor bar M' is fully depressed, it causes the main motor bar M to be depressed sufficiently for the hook 10 pivoted on the lever 36 to be moved by its spring 11 to engage under the stud 15 12 on the rearward portion of the lever 37 and latch the main motor bar in depressed position. If manual pressure is now removed from the special motor bar M', its spring 29a (Fig. 2) raises it together with the pivot 34 of the bell crank 33 somewhat. However, the latch 10, 12 prevents the rear end of the lever 36 from rising, and the bell crank 33 is, therefore, rocked counterclockwise about its pivot 34 until its lower arm engages against the stud 30 which then holds the special motor bar M' in a position intermediate its fully depressed position and its fully restored position until the latch 10, 12 is tripped to permit both motor bars to restore fully. When the main motor bar is released, the special motor bar will be carried upward with it as it returns to normal.

Depression of the special motor bar M' controls a skip-tabulating shaft 40 (Fig. 2), which is the same as the shaft 153 in Rinsche No. 1,580,534. When this shaft 40 is rocked slightly counterclockwise from the position of Fig. 1, it sets a "skip-tab" mechanism that is then latched in position. As previously mentioned, during normal tabulating movements, the tab bar 26 is rocked near the end of a machine cycle to release the paper carriage and said bar immediately returns to normal to arrest the carriage in the next columnar position. But when the "skip-tab" mechanism is set, as above mentioned, it acts, when the tab bar is rocked near the end of the machine cycle, to latch said tab bar against return to normal. Accordingly, the carriage will continue to move until it arrives in a column where a carriage cam releases the tab bar, whereupon said tab bar returns to normal and arrests the carriage in the predetermined column. In the present invention, said controls are set to arrest the carriage in the "deposit" column.

Since, in some cases, the special motor bar M' is depressed and immediately released and, in other cases, depressed and held down a short time, provision must be made for proper control of the "skip-tab" mechanism under both conditions.

Fixed to the shaft 40 is an arm 41 on whose free end is pivoted a pawl 42, spring urged clockwise by spring 42a. In the normal position of the parts shown in Fig. 1, the pawl limits against a stud 43 on an extension of the stem 29 of the special motor bar. The pawl 42 has an upstanding arm or finger 46 adapted, under certain conditions, to be positioned in the path of a stud 47 (Fig. 2) on the rear arm of a three-armed lever 48 pivoted at 49. The lower arm of this three-armed lever has a cam surface 51 positioned in the path of a stud 52 on the full-stroke sector 53. During a machine cycle, this full-stroke sector is first rocked counterclockwise from the position of Fig. 1 and then returned clockwise. Near the

end of the first half cycle the stud 52 engages the cam surface 51 and rocks the three-armed lever 48 clockwise, said lever 48 being returned clockwise by a spring during the early part of the last half cycle, or return stroke, of the machine.

The parts normally occupy the position shown in Fig. 1 and, if the machine is cycled by means of the main motor bar M, the three-armed lever 48 will be rocked as above mentioned but, since the upstanding finger 46 of pawl 42 is not in the path of stud 47, the "skip-tab" mechanism will not be set and the carriage will simply be given a normal tabulation from one column to the next. When the special motor bar M' is depressed, its stem 29 is lowered and the stud 43 moves away from pawl 42. The latter is then rocked clockwise by its spring until it limits against the stud 45 on arm 41, in which position, the finger 46 is in the path of the stud 47 on the three-armed lever 48. As the machine is cycled, and near the end of the first half cycle, the three-armed lever 48 is rocked clockwise whereupon stud 47 engages the finger 46 and rocks the arm 41 counterclockwise to set the "skip-tab" mechanism, the latter being then latched in set position. This does not cause the carriage to move immediately, but, when the tab bar is rocked near the end of the machine cycle, the "skip-tab" mechanism holds the tab bar and causes the carriage to move to the "deposit" column as above explained.

As the arm 41 rocks counterclockwise during the above operation, its free end moves in an arc toward the rear and the parts finally move to the position of Fig. 2 where the stud 43 occupies a slot in the pawl 42. During the second half of the cycle, the three-armed lever 48 returns to normal and stud 47 moves away from finger 46. When the "skip-tab" mechanism is released at the time the carriage arrives in the "deposit" column, arm 41 returns clockwise to normal position, at which time its free end moves forward slightly in an arc so that the edge of the pawl 42 is again in the path of the stud 43 on the stem 29 of the motor bar M'. Accordingly, when the motor bar M' returns to normal, the stud 43 engages pawl 42 and rocks it to the position of Fig. 1.

When the motor bar M' is depressed and manually held fully depressed a short time, that is, past the half cycle, the parts operate as above explained and no further description is necessary. But, if the operator withdraws manual pressure from the special motor bar M' immediately after fully depressing it, the motor bar at once returns part way toward normal position, as already explained. To insure that the finger 46 of the pawl 42 will be held in the path of the stud 47 whether the special motor bar is permitted to rise to its partially restored position or held in the fully depressed position slightly past the half cycle of the general operating means, the arm 41 carries a stud 45 positioned within a broad notch in the upper rear edge of the pawl 42 to stop clockwise movement of the pawl 42 at the point where the end of the finger is squarely in the path of the stud 47. Also, the lower edge of the rear portion of the pawl 42 is formed with a deep notch so that the counterclockwise movement of the arm 41 by the action of the stud 47 on the finger 46 will not be hindered by the pawl 42 striking the stud 45 whether the motor bar stem 29 is in its partially restored position or its fully depressed position at the end of the half cycle. According-

ly, the "skip-tab" mechanism will be properly set, both when the motor bar is depressed and held depressed for a time and when it is depressed and released immediately.

5 An interlock is provided for preventing depression of the special motor bar M' in columns where said bar should not be depressed. For this purpose a lever 60 (Fig. 1) is pivoted at 61 to the machine frame. This lever has an upper 10 extension carrying a stud 62 adapted to engage a notch 63 in the stem 29 of the motor bar M'. The other end of lever 60 has a lug 64 adapted to be engaged by a cam bar 66 mounted on the paper carriage. In the columns where the special 15 motor bar M' should be free for depression, the cam bar 66 rocks the lever 60 clockwise to disengage the stud 62 from the notch 63 in the motor bar stem. In all other columns, the lever 60 is free to be urged to latching position by its 20 spring 67 which causes a stud 62 to enter notch 63, thereby preventing depression of the motor bar M'. In Fig. 1, the parts are shown in the position they occupy in one of the columns where the motor bar M' is free for depression.

Control of automatic machine cycles

The manner in which the special motor bar M' is manipulated determines whether or not the machine shall be given an automatic cycle in a subsequent columnar position of the carriage, namely, the "deposit" column.

When the special motor bar M' is depressed, it carries the main motor bar M down with it, and the two bars are latched down as previously 35 explained. The counterclockwise movement of the lever 31, acting through a spring 73^a, raises the control link 73 to close the motor switch, engage the clutch, and cause the machine to be 40 given a cycle of operation. Near the end of the first half of the cycle, the stud 52 on the full-stroke sector 53 engages a projection on the link 73 and moves it downward to normal. This opens the motor switch and disengages the clutch, the machine going through its second half cycle under the urge of springs 23^a. The downward movement of link 73 tensions the spring 73^a because the motor bars are still latched down, and the tension of the spring tends to again 45 raise the link 73. Such movement of link 73 is 50 normally prevented, however, by the blocking latch 73^b (Fig. 8) as described in Muller 1,397,774. This latch moves over a stud 73^c on the link 73 to temporarily hold down the link, the latch being normally released by the stud 73^c carried 55 by the rear end of the lever 31 acting on a forward arm 73^e of the latch when the lever 31 moves clockwise when the motor bar M returns to normal. For a repeat cycle, said latch 73^b is 60 released by a carriage roll that acts when the carriage reaches its next position and while the repeat hook 70 keeps the motor bar latched down, all as described in said Muller patent and as explained in more detail later. Normally, 65 when no repeat cycles are wanted, the repeat hook 70 is released near the end of the machine cycle and prior to the time when the latch 73^b would be released by a carriage roll for a repeat cycle, whereupon the tension of spring 73^a restores the motor bar to normal and no second 70 cycle of machine operation occurs. But, if the repeat hook 70 is not released, then when the paper carriage moves to a position where a carriage roll effects the release of the latch 73^b.

the link 73 will rise again and close the switch and clutch to cause a second machine cycle.

The motor bars, as well as the keys of the machine, are normally released near the end of each machine cycle by a restoring mechanism shown in Figs. 1 and 2. This mechanism includes a restoring bail 100 that extends across the machine in position to engage the key release latches 101 for the key latching plates of the various banks of the machine. One of the side arms that support this bail extends upward as shown in Fig. 1 to a position such that it may, when rocked, engage the end of a latch slide 98, having a projection 99 adapted to engage the end of the repeat hook 70. This restoring means is normally rocked far enough counterclockwise near the end of the machine cycle to engage both the key releasing latches 101 and the motor bar latch plate 98, to not only release all the keys but to release the motor bars as well. However, said restoring means may be controlled so that it is moved only far enough to release the keys without releasing the motor bars. Such control governed automatically by a repeat slide positioned by the paper carriage is described in Muller No. 2,087,542, but in the present machine the control of the restoring mechanism depends mainly upon the manipulation of the special motor bar M'.

The releasing means is actuated near the end of the machine cycle by a three-armed member 89 pivoted at 90 (Fig. 2) and urged clockwise by a spring (not shown). In the normal position of the parts, shown in Fig. 1, a projection on the full stroke sector 53 engages an arm of the three-armed member 89 and holds it counterclockwise against the urge of its spring. During the first half of the machine cycle, the full-stroke sector moves counterclockwise which releases the three armed member 89 which thereupon follows the full-stroke sector in a clockwise direction. The rearwardly projecting arm of the three-armed member 89 carries two pawls 91 and 92 adapted to engage a roller stud 95 on the side arm 96 of the restoring means. These two pawls are of different size. The arrangement is such that, if, during the clockwise movement of the three-armed member, both of the pawls pass below the stud 95, so that the larger will engage said stud upon the return of the three-armed lever, then the restoring means will be rocked its full extent and both the keys and the motor bars will be released. But, if movement of the arm 89 is limited so that only the smaller of the two pawls passes below the roller stud, then said restoring means will be rocked a shorter distance, which distance is sufficient to restore the depressed keys but not to release the motor bar hook 70.

The special motor bar M' carries a stud 80 on a depending arm 81, which stud engages the cam edge of a lever 82 pivoted at 83 and urged clockwise by a spring 84 (Fig. 3). The parts normally occupy the position shown in Fig. 1, where stud 80 engages the cam edge of lever 81 above a notch 80a in said lever. When the special motor bar is depressed, stud 80 moves along the edge of the member 81 to a position below the notch 80a.

Lever 82 extends downward and its lower end is hook-shaped to provide a pocket 86 and an upwardly projecting lug 87. Both when the special motor bar is in normal position and while it is held fully depressed, the member 82 occupies the position of Fig. 6 where the lug 87 is rearward

75 of the path of a stud 88 on the three-armed member 89.

When the motor bar M' is depressed and held depressed during the first half cycle, the stud 80 moves below the notch 80a in the member 82 and holds the latter in the position of Fig. 3 so that, when the three-armed member 89 moves clockwise during the first half cycle, the stud 88 moves into the slot 86 in the member 82. This 10 allows the member 89 a full clockwise movement with the result that both pawls 91 and 92 pass the roller 95 so that, upon counterclockwise return movement of the three-armed member 89 during the latter half of the cycle, the restoring mechanism is operated for its full movement to release both the keys and the motor bar. The motor bar M' need be held depressed only long enough to permit the three-armed lever to complete its clockwise movement which it does during the first half cycle. Thus, in the present invention, when the motor bar M' is depressed and held depressed a short time with the paper carriage in either of the check columns, the machine will go through the cycle to perform the operations set up in the check column, after 15 which the cycle will stop and, for reasons previously explained, the carriage will tabulate to the "deposit" column and stop.

If, however, the motor bar M' is depressed and 20 immediately released, the stud 80 will be in a position opposite the notch 80a in member 82. This allows the member 82 to be positioned so that, when the three-armed lever 89 rocks clockwise, its stud 88 will engage the end of projection 87. This blocks full movement of member 89 so 25 that only the pawl 92 passes the roller 95. The result is that, upon the return movement of member 89, the release mechanism will be moved only far enough to release the keys and not far enough to release the motor bars. The result is 30 that the machine will be given another cycle of operation automatically but, in order to understand exactly what happens, the sequence of operations must be followed through.

The motor bar M' is depressed and released 35 immediately with the carriage in one of the check columns. The machine goes through a cycle to perform the necessary operation in this column and, near the end of the cycle, the paper carriage moves to the "deposit" column. Near 40 the end of said machine cycle, the pawl 92 on three-armed member 89 rocks the releasing mechanism but does not release the repeat hook 70. This occurs prior to the time the carriage reaches the "deposit" column. The machine is 45 thus set for a repeat cycle but this cycle does not occur until the carriage reaches the "deposit" column, owing to the presence of the blocking latch 73b heretofore described. But, when the carriage reaches the deposit column, the machine 50 immediately goes through a cycle. As said carriage arrives in the "deposit" column, a cam roll 105 (Fig. 1) acts as described in Muller 1,397,774 to rock a repeat lever 106 which, in turn, rocks a bell crank 106a (Fig. 5) to move a 55 repeat slide 107 rearward. Rearward movement of repeat slide 107 causes its hooked end 108 (Fig. 8) to release the blocking latch 73b whereupon the link 73 rises to give the machine another cycle. During the first half of this automatic cycle, the three-armed member 89 is again rocked clockwise and, if the motor bar M' were 60 still held down, the parts would be set for a third automatic cycle. Another cycle is wanted 65 for a positive total but not for a negative total.

While the paper carriage is in the "deposit" column, the carriage roll 105, which moves the bell crank 106^a and slide 107 to trip the latch 13^a as the carriage moved into said column, holds the bell crank 106^a in such a position that a second arm 106^b of said bell crank engages a stud 82^b on a rearwardly extending arm 82^c of the member 82 and holds the latter in a position such that the notch 88 is in the path of the stud 88 on the three-armed member 89. Consequently, during the automatic cycle of machine operation in the "deposit" column, the three-armed member 89 moves its full distance so that, during the latter half of said cycle, the restoring mechanism will operate to release the motor bars. Accordingly, insofar as the special motor bar M' is concerned, no repeat cycle will occur after the automatic cycle with the carriage in the "deposit" column. However, as will be presently explained, at the end of said cycle the paper carriage tabulates to the total-taking column and another automatic operation may take place under control of mechanism that will be described in connection with total taking.

Thus, the special motor bar M' controls mechanism such that, if said bar is depressed and held depressed a short time, the machine will go through only one cycle, which is the cycle in the column where the bar is depressed, after which the carriage will move to the "deposit" column and stop. But if said motor bar M' is depressed and instantly released, the machine will go through the cycle in the column where said bar is depressed, the carriage will move to the "deposit" column, the machine will go through another cycle automatically, and the carriage will then move to the total-taking or "balance" column.

Automatic total-taking mechanism

When the paper carriage moves into the total-taking or "balance" column, the total-taking control means is automatically conditioned for total taking and the machine goes through a total-taking cycle automatically, provided the total is positive.

The machine is equipped with a mechanism for eliminating one of the spacing cycles which were at one time necessary on the Burroughs machine, said mechanism being described in Muller 1,844,070. It is also equipped with a mechanism such as shown in said patent for causing the machine to be given a cycle of operation when the total-taking means is conditioned for total taking.

As the carriage moves into the "balance" column, a large carriage roll 109 similar to the large roll 33 shown in Fig. 2 of Muller No. 2,087,542 engages the repeat control lever 106 to move the repeat slide 107 from the full-line position of Fig. 5 to the dotted-line position of said figure. This full rearward movement of the repeat slide normally causes a power means automatically to move the total-taking control means to total-taking position and movement of the latter causes an automatic machine cycle as will now be explained.

When the repeat slide 107 is moved rearward to the dotted-line position of Fig. 5, an upper arm 108 thereof engages one arm 111 of a bail-like latch 112 and rocks the latch arm 113 of said bail counter-clockwise (Fig. 5) to release a lever 114, permitting the latter to be rocked clockwise on its pivot 115 by a spring 116 from the position of Fig. 1 to that of Fig. 5. As lever 114 moves clockwise, it engages a lug 117 on another lever 118 also piv-

oted at 115 and urged counter-clockwise by spring 118. This rocks lever 118 clockwise, the spring 118 being stronger than spring 116. Clockwise movement of lever 118 causes its notched end 120 to move upward and become disengaged from a lug 121 on a rearward projection of a lever 122 pivoted on shaft 123 and urged clockwise (Fig. 1) by a strong power spring 124. When said lever 122 is thus released by the carriage acting 10 through the train of parts just described, it is moved by the power spring from the position of Fig. 1 to that of Fig. 5. This power spring constitutes the power means for moving the total-taking control means to total-taking position.

15 Lever 122 has an upwardly and forwardly projecting arm 126 adapted to engage a stud 127 on a T-shaped lever 128 that is a part of the Burroughs total control means and which is fixed to the shaft 123. Referring to Fig. 4, said shaft 123 extends across the machine and it has an arm 129 fixed to its right-hand end, which arm is connected by a link 131 to the bell crank 130 carrying the total key T. When the arm 122 (Fig. 5) is moved by the power spring 124 the lever 128 is moved from the dot-dash to the full-line position of said figure. This rocks the shaft 123 clockwise in Fig. 5 which is counter-clockwise in Fig. 4. Such movement of shaft 123 in Fig. 4 rocks the bell crank 130 clockwise which is the same direction of movement given it when the total key is depressed. The rocking of shaft 123 also causes the spring 123^a (Fig. 1) to move the link 123^b rearward as described in Muller 1,844,070. A stud 123^c on said link rocks bell crank 123^d clockwise which acts through a spring 123^e (Fig. 1) to operate the motor switch and clutch and causes the motor drive to give the machine a cycle of operation.

Thus, when the carriage moves into the "balance" column, it causes a power means to move the total-taking control means to total-taking position and the movement the latter causes the power drive of the machine to give said machine a cycle of operation during which the total is taken.

45 The total-taking control means and its power spring are returned to normal as follows:

During the first half of the machine cycle in total taking, the stud 52 on the full-stroke sector 53 engages the cam edge 51 on the three-armed lever 48 and rocks it clockwise as previously explained. Pivoted to the upper and forward arm 138 of the three-armed lever 48 is a pawl 136 (Figs. 2 and 5) having a hook portion 137 and a notch 138, the pawl being urged clockwise by a spring 139. When the lever 48 is moved clockwise by full-stroke sector 53 during the first half of each cycle, the pawl 136 is moved to the right, but, as long as the total lever 128 is in its normal left-hand position, this has no effect because the stud 127 on lever 128 engages the top of the hooked end of pawl 136 and holds it down so that shoulder 138 will not engage stud 141. But, after the total lever 128 has moved to the right for a total-taking cycle, and when lever 48 moves pawl 136 during the first half of the total-taking cycle, the notch 138 of pawl 136 engages a stud 141 on a latch 142 and rocks said latch clockwise against the action of its spring 143 and thus disengages the forward hooked end 144 of said latch from an anchor lever 146 pivoted at 147. The other end of lever 146 forms the anchor for the power spring 124. After the power spring 124 has acted to pull the total-taking control means to total-taking position, its tension has been largely re-

lieved and when the latch 142 is released both said spring and its anchor 146 are free for movement. A relatively light spring 150 (Fig. 2) then acts to swing lever 122 counterclockwise and said lever, acting through spring 124, swings the anchor lever 146 counterclockwise, the movement of the parts being limited by engagement of lever 146 with the stud 52 in the full-stroke sector 53 which, at the time, is in its lower position. As the sector 53 returns to normal during the second half of the cycle, the anchor lever 146 follows stud 52 and moves to the dot-dash position of Fig. 5 which allows lever 122 to move to its normal position under the urge of spring 150. As the three-armed lever 48 is rocked clockwise during the first half of the machine cycle in total taking by the engagement of stud 52 on the full-stroke sector 53 with the cam edge 51 on the lever 48, its upper forward arm 135 engages a depending finger 153 of lever 114 and rocks the latter counterclockwise to move its rear end above latch 113 which thereupon snaps over the end of said lever 114 to hold it in position. The latch 113, when it was tripped by the slide 107, was allowed to move back toward latching position because the large roll on the carriage passes slightly over the high point of its lever so that slide 107 is moved fully rearward and then allowed to come back slightly. The restoration of lever 114 also releases the lever 118 which is thereupon moved by its spring so as to move its notched end 120 to a position such that, as said lever 122 returns to normal during the latter half cycle, the notched end 120 will snap over the lug 121 on lever 122. Thus, lever 122 is again latched in its normal position. During the second half of the total-taking machine cycle the three-armed lever 48 is released and it returns counterclockwise to normal under the urge of its spring. This moves the hooked pawl 136 forward and releases the latch 142 which tends to return to normal under the urge of its spring. Said latch 142 cannot return immediately because the anchor lever 146 occupies the dot-dash position of Fig. 5. Instead, the edge of said latch 142 rests on the lug on the end of lever 146. During the first half of the next machine cycle, the stud 52 on full-stroke sector 53 rocks the anchor lever 146 clockwise until the latch 142 snaps over it. This retensions the spring 124 and thus reocks the power means that operates the total-taking control means.

The spring 123 is retensioned and the link 123^b is restored to normal during the total-taking cycle by a lever 123^c (Fig. 1) which is rocked by the general operating mechanism of the machine as described in Muller 1,844,070.

The lever 123, shaft 123 and the total key cannot start their return to normal immediately when the lever 122 and arm 125 begin to move toward their normal positions. A roller 128^a (Fig. 5) on the lower end of the lever 128 cooperates with an arcuate flange 53^a on the full stroke sector 53 to prevent movement of the lever 128, shaft 123 and total key during cycles of operation of the machine. At the beginning of the cycle of operation, the full stroke sector 53 rocks counterclockwise and carries the flange 53^a down on one side or the other of the roller 128^a, depending on the position of the lever 128, the shaft 123 and the total key at the time, and prevents these parts from changing their positions during the cycle, but as the full-stroke sector 53 returns clockwise to its normal position at the end of the cycle, the lower end of the flange 53^a is raised above the roller 128^a so that

the lever 128, shaft 123 and the total key can be restored at the end of the total taking cycle by the usual spring corresponding to that numbered 123^a in the Muller Patent 2,087,542.

5 Control of automatic machine cycles by sign of total

When the carriage moves into the "balance" column with a negative total in the main registering mechanism or "crossfooter," the machine will not be conditioned for total taking nor will an automatic machine cycle occur. This is true no matter whether the preceding operation involved entering a deposit in the "deposit" column or whether the machine went through an automatic spacing cycle in said "deposit" column.

Referring to Fig. 4, a three-armed lever or "setting member" 160 is provided which is pivoted at 161 and which may be set in either of two positions depending upon the sign of the total in the "crossfooter." Said member is releasably held in the position to which it is set by a spring detent 162. Its position is determined by cams, such as the cams 16 and 17 (Fig. 1) on the highest order add and subtract pinions in the manner described in detail in Pasinski 1,778,506 and Muller 2,087,542. When the total in the "crossfooter" is positive the "setting member" occupies the position illustrated in full lines in Fig. 4 whereas, when the "crossfooter" goes negative, the member is moved counterclockwise to the dot-dash position of Fig. 4. The reverse action takes place when the "crossfooter" changes from negative to positive condition.

35 The upper arm of the member 160 carries a stud 163 operating in a slot 164 formed in the forward end of a link 165 that is connected to the member 14^m which, after the position of the subtract lever is changed, is moved to add or subtract position 40 as the case may be during a machine cycle. The slot 164 has two notches in its upper edge as shown in Fig. 4.

When the total is positive the member 160 is in its forward full-line position of Fig. 4. If the add-subtract controlling means is in add position at that time, the link 165 occupies its rear-most position and the stud 163 is in the forward notch of slot 164. The parts are then in what may be called normal or nonlocking condition.

When the paper carriage moves into the "balance" column, the add-subtract controlling means is always in add condition either as a result of a "deposit" entry in the preceding column or as the result of an automatic spacing cycle.

If, with the add-subtract controlling means in add condition, the total is negative, the member 160 occupies the dot-dash position of Fig. 4, in which position the stud 163 contacts the upper edge of the slot 164 between the two notches in said slot, and the link 165 is raised as shown in dot-dash lines in Fig. 4. This raising of the link 165 is utilized to prevent the automatic total-taking cycle in the "balance" column. In actual operations, the total goes negative at the time a check is subtracted, and it is the movement of link 165 at the time the add-subtract controlling means is moved to add condition that moves the parts to the position above explained. The control of the automatic cycle is as follows:

The upper edge of link 165 contacts a stud 166 on an arm 167 which is part of a yoke-like member 168 pivoted at its top as shown in Fig. 4 and urged counterclockwise by a spring as will be presently explained. This yoke extends across the machine and, at its other side, has an integral

arm 175 (Fig. 1) provided with a shoulder adapted to engage over a lug on the arm 176 as shown in Fig. 2. The arm 176 is an extension of lever 122 which is the lever that is operated by the power spring 124 to condition the total-taking control means for total taking.

When the total is positive and the add-subtract control mechanism is in add position, the arm 176 is free for movement. But, if the total is negative, the movement of the link 165 (Fig. 4) rocks the ball 168 clockwise in Fig. 4, or counterclockwise in Fig. 1. This moves the shoulder of arm 175 over the arm 176 and blocks movement of lever 122. Consequently, when the carriage arrives in the "balance" column with a negative total in the "cross-footer" and when said carriage releases the mechanism for an automatic total-taking cycle, said cycle will not occur and the operator will know that a negative total exists. Such notification will occur before a total is taken.

The above blocking of the machine against an automatic cycle also locks the total key T. This takes place through the medium of a lever 171 (Fig. 4) yieldingly connected by a spring 170 to the arm 169 of ball 168. When said ball is rocked clockwise under the conditions above explained, the upper end of arm 171 is moved under a stud 172 on the bell crank 130 carrying a total key, thus blocking depression of said key. This takes place against the tension of a spring 171^a that urges arm 171 clockwise and which is the spring heretofore mentioned that urges the ball 168 counterclockwise in Fig. 4.

When the machine is blocked against operation, it may be desirable, nevertheless, to take and print the negative total. This may be done as follows:

The operator moves the subtract lever 14 forward to subtract position. This conditions the machine so that the "crossfooter" will be tumbled to subtract position during the next machine cycle. But the movement of the subtract lever does not move the link 165 forward because said link is connected to a portion of the add-subtract control means that moves as the cross-footer frame is "tumbled" during the first half of said machine cycle. The operator then depresses the regular motor bar M, which causes a machine cycle during which the "crossfooter" is tumbled from add to subtract position during the first half of the cycle. During the early part of this machine cycle, the link 165 is moved forward so that the rearmost notch in the slot 164 is in register with the stud 163. The link 165 can then move down and, in so far as link 165 is concerned, the ball 168 will be released for counterclockwise movement. If the ball 168 were to move to released position immediately, its arm 175 would release the arm 176 of the power operated member 122 for operation by the strong spring 124 and it might be thought that the machine would be conditioned for total taking during the early half of the spacing cycle. But this does not occur for the following reason:

Referring to Fig. 2, it will be observed that, in a normal position of the parts with the lever 122 latched by the latch 118, the arm 176 is slightly below the shoulder of the arm 175 so that the ball 168 is free for movement. When the paper carriage went into the "balance" column the latch 118 was released, whereupon the strong spring 124 pulled the lever 122 a short distance to cause the arm 176 to engage the shoulder on arm 175. The spring 124 is so strong

that a very considerable frictional resistance between 176 and 175 is present. This prevents the light spring 171^a (Fig. 4) from pulling the ball 168 to released position when it is released by link 165 as above explained. The three-armed lever 48, which is rocked clockwise by the stud 52 on the full-stroke sector 53, has a pin and slot connection 180 (Fig. 2) with a bell crank 181 pivoted at 182. The forwardly extending arm 183 of this bell crank has a cam edge engaging a stud 184 on an extension of the member 122. Near the end of the first half of the spacing cycle, the stud 52 on the full-stroke sector rocks the three-armed lever 48 clockwise which rocks the bell crank 181 counterclockwise and the cam edge of arm 183 rocks the lever 122 slightly counterclockwise against the tension of the spring 124, there being sufficient force to do this owing to the fact that the full-stroke sector 53 is moved directly by the motor. Consequently, the friction contact between the arms 176 and 175 is relieved, and the ball 168 moves to released position. The above movement of lever 122 is sufficient to permit the latch 118-120 to snap back to position behind lug 121 on the member 122, said latch being released during the first half of the spacing cycle by the clockwise movement of the three-armed lever 48 as described in connection with the restoration of these parts. The return of latch 118-120 to latching position locks lever 122 and thus prevents the power spring 124 from moving the total-taking control means to total-taking position.

Since the operator depressed the regular motor bar for the spacing cycle, the machine will stop after going through said cycle and the carriage will not tabulate because the tabulating mechanism is disabled or "normalized" automatically as the carriage moves into the "balance" column as disclosed in the Muller Patent 2,087,542 and is reenabled only when the total-taking control means is set for total taking as also disclosed in said Muller patent. Consequently, the carriage will remain in the balance column until the machine is cycled with the total key depressed.

The operator continues to hold the subtract lever in subtract position and then depresses the total key, which causes the total-taking control means to be conditioned for total taking and the machine to be given a total-taking cycle as in Muller 1,844,070.

If, at the time he enters a check, the operator knows that it will cause an overdraft and, if he nevertheless wants to obtain and print the negative total, he can speed up the operation of the machine by operating it in a modified manner as follows: After he has indexed the check on the amount keys, he puts his finger on the subtract lever to hold it in subtract position and then depresses the special motor bar M' and releases it immediately, continuing to hold the subtract lever in subtract position. The machine will go through a cycle in the check column and subtract the check from the "crossfooter," thereby causing the latter to go negative. Near the end of the cycle, the carriage will move to the "deposit" column where the machine will go through an automatic spacing cycle, the operator continuing to hold the subtract lever in subtract position. This is an idle cycle since the machine is already in subtract condition with the total in the "crossfooter" negative. Near the end of this automatic cycle, the carriage will tabulate to the "balance" column. The operator continues to hold the

subtract lever in subtract position and when the carriage reaches the "balance" column the machine will go through a total-taking cycle automatically because the machine is in subtract condition and the total in the "crossfooter" is negative so that the parts heretofore explained will be released and the power spring 124 will condition the machine for total taking and cause a negative total to be taken. This mode of operation can be used when the operator knows there is a negative total and when he desires to print it nevertheless.

It will be obvious to those skilled in the art that the principles of this invention may be applied to other machines and that many variations in the details may be made without departing from the spirit and scope of the invention as defined in the appended claims.

I claim:

1. A calculating machine of the class disclosed having a motor operated driving means, drive control means conditionable to cause said driving means to give said machine a cycle of operation, means operable to condition said control means, manipulative means, including a depressible motor bar, for operating said conditioning means, means for retaining said conditioning means in operated position when operated, and means movable automatically at a predetermined time in the machine cycle to a position to release said conditioning means from said retaining means, said manipulative means including elements conditioned by depression of said motor bar and continued manual pressure thereon beyond said predetermined time in the machine cycle to permit said releasing means to move to said releasing position and release said conditioning means to return to said unoperated condition without causing a further machine cycle, said elements being conditioned by depression of said motor bar and withdrawal of manual pressure therefrom prior to said predetermined time in the cycle initiated by said depression to prevent said releasing means from moving to said releasing position in said machine cycle whereby said conditioning means is retained by said retaining means in its operated position to condition said drive control means to cause an automatic further cycle of operation of said machine.

2. A calculating machine of the class described, having a motor operated driving means, manipulative means conditionable to two out-of-normal conditions, drive control means conditionable by

said manipulative means to cause said driving means to give the machine a cycle of operation, means normally movable during each machine cycle initiated by the conditioning of said manipulative means, means operable automatically under control of said movable means to control said drive control means for causing said driving means to give the machine an automatic second cycle of operation following the cycle initiated by the conditioning of said manipulative means, and means conditioned by said manipulative means in one of said out-of-normal conditions to prevent effective control of said drive control means by said automatically operable means under control of said manipulative means in the other of said out-of-normal conditions to permit effective control of said drive control means by said automatically operable means under control of said automatically movable means.

3. A calculating machine of the class described, having a motor operated driving means, manipulative means conditionable to two out-of-normal conditions, drive control means conditionable by said manipulative means to cause said driving means to give the machine a cycle of operation, a traveling paper carriage normally automatically moved to a new position toward the end of each machine cycle, means controlling the movement of said carriage and conditioned by said manipulative means when the latter is placed in either of said out-of-normal conditions to cause the carriage to move near the end of the ensuing machine cycle directly to a predetermined position and skip any intervening position, drive repeat means operable by movement of said carriage to said predetermined position to control said drive control means for causing said driving means to give the machine an automatic second cycle of operation following the cycle initiated by the conditioning of said manipulative means, and means conditioned by said manipulative means in one of said out-of-normal conditions to prevent effective control of said drive control means by said drive repeat means by movement of said carriage but conditioned by said manipulative means in the other of said out-of-normal conditions to cause effective control of said drive control means by said drive repeat means by movement of said carriage.

ROBERT L. MULLER.
